UNITED STATES PATENT OFFICE.

ISAAC ARYNSAN LUND, OF CHICAGO, ILLINOIS.

DESIGN FOR A RADIOCABINET.

Application filed June 15, 1928. Serial No. 27,139. Term of patent 3½ years.

To all whom it may concern:

Be it known that I, ISAAC A. LUND, a citizen of the United States, residing in the city of Chicago, in the county of Cook and the State of Illinois, have invented a new, original, and ornamental Design for Radiocabinet, of which the following is a specification, reference being had to the accompanying drawings, forming a part thereof.

In the drawings:—

Figure 1 is a front view in perspective

showing a radio cabinet embodying my new design.

Figure 2 is a top plan view of the same.

I claim:—

The ornamental design for a radiocabinet substantially as shown.

In testimony whereof, I have hereunto set my hand at Chicago, Illinois, this 12th day of June, 1928.

ISAAC ARYNSAN LUND.
